PORTABLE SHOWER BATH ASSEMBLY

Harvey L. Burnett, 201 N. Pine St., De Ridder, La.

Filed Aug. 3, 1962, Ser. No. 214,735

1 Claim. (Cl. 4—145)

This invention relates to shower bath facilities, and more particularly to a portable shower apparatus.

A main object of the invention is to provide an inexpensive means for bathing where running water is not readily available.

A further object of the invention is to provide a novel and improved shower enclosure which is portable and uncomplicated, being easy to set up, being simple to operate, and affording a maximum amount of privacy to the user.

A still further object of the invention is to provide an improved shower enclosure which is constructed of relatively inexpensive materials, being durable, being easy to fabricate, and being independent of a water source.

Further objects and advantages of the invention will become apparent from the following description and claim, and from the accompanying drawings, wherein:

FIGURE 1 is a perspective view with a portion broken away of a shower bath assembly constructed according to the present invention, showing the shower enclosure and the accompanying water tank, as the apparatus is set up for use;

FIGURE 2 is an enlarged vertical cross-sectional view of the water tank employed in FIGURE 1, taken substantially on the line 2—2 of FIGURE 1;

FIGURE 3 is a vertical cross-sectional view of a shower enclosure taken substantially on the line 3—3 of FIGURE 1;

FIGURE 4 is a horizontal cross-sectional view taken substantially on the line 4—4 of FIGURE 3;

FIGURE 5 is an enlarged partial horizontal cross-sectional view taken substantially on the line 5—5 of FIGURE 3;

FIGURE 6 is a vertical cross-sectional view taken substantially on the line 6—6 of FIGURE 5; and

FIGURE 7 is an exploded view of the shower enclosure showing the manner of assembly of the enclosure from its various component members.

Referring to the drawings, and more particularly to FIGURES 1 and 2, it will be seen that the invention generally comprises a water tank 11 and a shower enclosure 12. The water tank 11 is a closed container constructed in such a manner that it may withstand relatively high internal pressures. The water tank 11 is provided at its top wall with an externally threaded filling conduit 13 and an airtight cover 14 for said filling conduit 13. Also provided on tank 11 is a water outlet valve fitting 15 from which extends a piece of tubing 16 downwardly into the tank 11, terminating closely adjacent to the bottom of the tank. Also provided on tank 11 is a water level indicator comprising a float ball 17, a guide stick 18, a guide tube 19 secured vertically to and depending from the top wall of the tank, and an airtight winged top cover cap 20 therefor. The guide tube 19 projects a short distance above the top wall of the tank 11 and is provided with external threads, and the cover cap 20 is provided with internal threads threadedly engageable with the external threads of the top portion of tube 19.

The ball 17 is constructed of buoyant material or may be hollow, serving as a float, so that it tends to seek the surface of the water in the tank. A portion 21 of the guide stick 18 near the ball 17 is distinctively colored.

When the winged cover 20 is removed, the ball 17 moves with the level of the water as the tank is filled

2

through the filling conduit 13. The guide stick 18 moves upwardly through the guide tube 19, until the colored portion 21 comes into view, thus indicating that the necessary amount of water has been added to the tank.

5 The guide stick 18 and ball 17 may then be enclosed in the tank by pushing the stick 18 downwardly so that its top end is below the level of the top end of tube 19, after which the winged cover 20 is screwed on the externally threaded top portion of tube 19.

Tank 11 is also provided with an air valve 22 and an air pressure gauge 23, which is equipped with a safety valve. The air valve 22 is a one-way check valve, permitting air to be pumped into the tank but preventing any outward flow. The pressure gauge 23 is calibrated in pounds per square inch, and the safety valve built therein is set to release air when the pressure exceeds a predetermined safe amount.

The tank 11 is also provided with two diametrically opposed carrying handles 24, 24.

Referring to FIGURES 1 and 3—7, shower enclosure 12 comprises a floor assembly 24, a shower curtain 25, four vertical supporting poles 26, four horizontal supporting poles 27, and a shower head 35.

The floor assembly 24 comprises a plurality of floor boards or slats 28 hinged together by links 29 in such a manner that the floor 24 may be folded or rolled up into a compact unit. On each link 29 is provided an outwardly projecting male snap fastener member 30, and similar male snap fastener members 30' are provided on the outer edges of the two end slats or boards 32, 32 of the floor assembly 24, so that the floor assembly 24 is completely provided around its periphery with male snap fastener members 30, 30' uniformly spaced around said periphery.

35 Secured to the end portions of the end slats or boards 32, 32 are respective upstanding sleeve-like sockets or receptacles 33 for supporting poles, being thus located at corners of the floor assembly 24.

Shower curtain 25 is constructed of a durable waterproof material such as canvas, sheet plastic material, or the like, being of sufficient height to reach the horizontal supporting poles 27, and being of sufficient length to extend around the perimeter of the enclosure. The curtain 25 is provided with female snap fastener elements 130, 130' located to engage with the floor snap fastener members 30, 30'. Curtain 25 is also provided with rings 34 which are adapted to encircle the horizontal supporting poles 27. A slide fastener 34' is provided on the vertical edges at the respective ends of the curtain 25 so that it may be employed to detachably secure said vertical edges together and thus to at times completely enclose the shower frame.

The vertical supporting poles 26 fit into the sockets or receptacles 33 on the floor assembly 24. They extend upwardly and are joined at their top portions by the horizontal supporting poles 27. The structure of the connections between the vertical and the horizontal poles is shown in detail in FIGURES 5 and 6, and is such that it may be readily assembled and disassembled. Each vertical pole 26 is provided near its top end with two L-shaped rods 36 which are mounted at right angles to each other and which extend upwardly. The L-shaped rods 36 are engageable with aligned holes 37 provided near the ends of the horizontal poles 27.

65 The shower head 35 is connected to the water tank 11 by means of a flexible connecting hose 38, which is connected by screw couplings to the shower head 35 at one end and the outlet valve fitting 15 of the tank 11 at the other end.

70 Shower head 35 is provided with a valve 39 which may be used to regulate the flow of water through the

shower head. The head is mounted on one of the horizontal supporting poles 27 by means of a clamping bracket 40.

In using the invention, the water tank 11 is first filled by unscrewing the winged cover 20 and filling conduit cover 14, and by pouring water into the filling conduit 13 until the colored portion 21 of the level-indicating stick 18 is visible outside the guide tube 19. The two covers 20 and 14 are then replaced, the guide stick being depressed as above described, whereby the tank is sealed with the level-indicating stick 18 and float 17 in a depressed position. Air is then pumped into the tank through air inlet valve 22 by means of a conventional tire pump. The air is compressed until the pressure gauge 23 reads the necessary amount required to force the water through the sprinkler head. The pump is then detached, and the tank is ready for use.

The shower enclosure 12 is assembled. The floor 24 is unrolled and laid out and the vertical poles 26 are inserted into the floor sockets or receptacles 33. The curtain 25 is unfolded, and the horizontal poles 27, each in turn, are first inserted through the rings 34 of the curtain 25, and are then mounted on the L-shaped rods 36 of the vertical poles 26. The bottom of the curtain 25 is then fastened to the floor 24 by means of the snap fastener members 30, 30' and 130, 130'. The slide fastener assembly 34' is thereafter used for opening and closing the shower enclosure, namely, for entering and leaving same.

The slide fastener is preferably of a conventional type which may be operated either from the inside or the outside of the enclosure, namely, which may be provided with operating tabs connected to the slider element thereof and extending respectively inside and outside of the enclosure.

The shower head 35 is mounted on a horizontal supporting pole 27 by means of the clamping bracket 40. The connecting hose 38 is connected to the shower head 35 and to the tank outlet valve fitting 15. The shower is then ready for use. The outlet valve 15 is opened, and the user may then regulate the flow of water from the

shower head as desired by manipulating the shower head valve 39.

While a specific embodiment of a portable shower apparatus has been disclosed in the foregoing description, it will be understood that various modifications within the spirit of the invention may occur to those skilled in the art. Therefore it is intended that no limitations be placed on the invention except as defined by the scope of the appended claim.

What is claimed is:

A portable shower bath assembly comprising a foldable floor comprising a plurality of parallel slats and respective link bars hingedly connecting the ends of adjacent slats to each other, a generally rectangular upstanding collapsible frame comprising vertical corner posts and horizontal connecting bars detachably connected to the top ends of said vertical corner posts, respective upstanding sockets on the end portions of the opposite end slats of said floor receiving the lower ends of said vertical corner posts, a flexible cover surrounding said frame, means detachably connecting the top margin of said cover to said horizontal connecting bars, means detachably connecting the bottom margin of said cover to the floor slats, whereby to define a shower stall, a shower bath sprinkler head secured to one of said horizontal connecting bars and directed downwardly and inwardly into said shower stall, a water tank, means to admit water into said tank, conduit means connecting the lower portion of said water tank to said sprinkler head, means to seal said water tank, and an air inlet check valve on the top of said tank, whereby air may be pumped into the upper portion of the tank to develop a pressure sufficient to force the water in the tank through said conduit means for discharge at said sprinkler head.
